SUGAR MEASURING CAP WITH DISPENSING SPOUT FOR JAR TOP USE

Rosewell G. Capron, 303 S. Recker Road,
Mesa, Ariz. 85206

Filed Mar. 24, 1975, Ser. No. 561,281

Term of patent 14 years

Int. Cl. D7—06

U.S. Cl. D7—131

FIG. 1

FIG. 3

FIG. 2

FIG. 4

FIG. 5

FIG. 1 is a top front perspective view of a sugar measuring cap with dispensing spout for jar top use showing my new design;

FIG. 2 is a bottom rear perspective view thereof;

FIG. 3 is a top plan view thereof partially in section;

FIG. 4 is a side elevational view thereof partially in section; and

FIG. 5 is a bottom plan view thereof.

I claim:

The ornamental design for a sugar measuring cap with dispensing spout for jar top use, as shown and described.
